UNITED STATES PATENT OFFICE

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK

CUTTING AND PERFORATING MACHINE

Application filed January 5, 1928. Serial No. 244,638.

This invention relates to a cutting or perforating machine, that is, a machine for severing a web of flexible material transversely either partially or wholly, and to a combined machine for both slitting and severing a web.

The invention relates more particularly to the type of machine in which the flexible material is wound after being acted upon. In machines of this type it is a well-known fact 10 that the slitting operation may affect adversely the winding operation and vice versa, but it is not generally recognized that a transverse severing operation, such as perforating, may likewise affect adversely both the slitting and winding operations. The main object and feature of this invention is to properly coordinate the transverse severing means with slitting and winding means although I 15 wish it to be distinctly understood that the invention is not limited to the inclusion of slitting or/and winding means.

In the accompanying drawings the invention is disclosed in a concrete and preferred form in which:

25 Fig. 1 is a transverse sectional view through a combined slitting and perforating machine embodying one form of the invention;

Fig. 2 is a top plan view, partly in section, 30 of the upper portion of Fig. 1;

Fig. 3 is a vertical sectional view substantially on the plane of line 3—3 of Fig. 2;

Fig. 4 is a detail sectional view showing 35 the perforating couple;

Fig. 5 is a more or less diagrammatic view showing the adjustable gearing;

Fig. 6 is a detail sectional view substantially on the plane of irregular line 6—6 of Fig. 3;

40 Fig. 7 is a somewhat diagrammatic view showing the adjustability of the perforating blade;

Fig. 8 is a detail view looking in the direction of arrow 8 of Fig. 7;

45 Fig. 9 is a perspective detail view of a spacing member that may be used in connection with the invention.

1 and 2 indicate two surface winding drums with which is associated a winding shaft 3. 4 and 5 denote two rotary members

to sever, in this case partially, a web 6 of flexible material transversely. 7 is a score-cut slitting means which acts against a suitable backing roll, here front winding drum 1, and this latter is provided with a glass-hard surface to resist the tendency of the score-cutters to mark or groove the backing roll. In this case web 6 is led over suitable guides to the front winding drum where the slitting action takes place, then between rotary members 4 and 5 where the perforating takes place and then back to the front winding drum and to the winding shaft. It will be understood that the slitted sections of flexible material should be disturbed as little as possible in order not to interfere with the winding operation and also that distortion of the slitted section should be avoided in order not to interfere with the slitting operation. With this object in view the surface speed of the rotary members is made the same as the surface speed of the backing roll. It will, however, be understood that it may be desired to vary the distance between successive lines of severance and therefore means are provided whereby this may be accomplished without varying the surface speed of the perforating elements.

The specific elements employed in the present instance are as follows:

Rotary member 5 is provided with a yielding surface 8 and rotary member 4 carries one or more projecting severing members such as perforating blade 9. This perforating blade preferably extends non-radially and has a trailing action during its cutting action. This blade does not cut into the yielding surface but simply depresses the latter at the point where it engages it and in order not to have the blade act against the same point all the time the circumference of member 5 is somewhat larger than the distance between successive lines of severance or multiples thereof. Blade 9 rests on a shelf 10 of member 4 and is provided with elongated slots 11 through which pass bolts 12 and it will be understood that by these means the cutting radius of said member 4 may be increased or decreased and thereby the distance between successive lines of severance

varied. Instead of, or in addition to, the foregoing other means may be employed such as a spacer block 13, having an elongated slot 11^a, which is inserted between shelf 10 and blade 9 and which when used will cause said blade to project further outwardly. To compensate for such adjustments, provision is likewise made whereby the center distance between 4 and 5 can be varied and this is 10 preferably effected by mounting member 4 in an adjustable bearing 14 slidably carried by the framework. Suitable driving connections are employed whereby the surface speed of member 4, that is of the cutting edge 15 of blade 9, may be maintained equal to that of member 5, or of the depression caused in its surface by blade 9, and equal to that of backing roll 1. In the present instance this is accomplished as follows: Drum 1 is provided with a gear 15 which engages a pinion 16 that in turn meshes with gear 17 of member 5, and said member 5 obviously need not be of the same diameter as drum 1 but can be provided with the same surface speed as said 25 drum by employing a proper gear ratio between the two. Meshing with gear 17 is a pinion 18 and pivotally mounted on a center in line with the center of rotation of pinion 18 is an arm 19 carrying a pinion 20 that 30 transmits motion from 18 to gear 21 on member 4. Arm 19 can be secured in any position to which it has been adjusted by bolt 22 and segmental slot 23. It will now be understood that, when blade 9 is adjusted to vary 35 the cutting radius of member 4, the same surface speed can be maintained by substituting other gears in place of 20 and 21 and that arm 19 can be adjusted to admit of this.

Drum 1 can be driven in any suitable 40 way, as by means of pinion 24 meshing with gear 25 on the drum, and it will be understood that drum 2 can be driven from 1 by means of pinion 26 and gear 27.

I claim:

- 45 1. Transverse severing means for webs of flexible material including: two rotary members, a cutting member adjustably mounted on one of said rotary members to increase or decrease the cutting radius thereof to thereby vary the distance between successive lines of severance, and driving connections to impart equal surface speed to the two rotary members notwithstanding changes in the cutting radius of one of said members, said connections including a power transmitting member adapted to be readily displaced to permit introduction of a different size power transmitting member in said driving connections.
- 50 2. Transverse severing means for webs of flexible material including two rotary members one provided with a yielding surface and the other with a projecting cutting member, said projecting cutting member adjustably mounted on said other rotary

member to increase or decrease the cutting radius thereof to thereby vary the distance between successive lines of severance, and driving connections to impart equal surface speed to the two rotary members notwithstanding changes in the cutting radius of one of said members, said connections including a power transmitting member adapted to be readily displaced to permit introduction of a different size power transmitting member in said driving connections.

Signed at the borough of Brooklyn, in the county of Kings, city and State of New York, this 22 day of December, 1927.

ROBERT McC. JOHNSTONE.
